By *Richard D. Owen* Attorney

UNITED STATES PATENT OFFICE.

WILLIAM S. THELLMAN, OF NEW CASTLE, PENNSYLVANIA.

RADIATOR SHUTTER.

Application filed September 25, 1923. Serial No. 664,753.

To all whom it may concern:

Be it known that I, WILLIAM S. THELLMAN, a citizen of the United States of America, residing at New Castle, in the 5 county of Lawrence and State of Pennsylvania, have invented certain new and useful Improvements in Radiator Shutters, of which the following is a specification.

The present invention relates to a radiator 10 shutter and has for its principal object to provide a device used in conjunction with an automobile radiator or the like for preventing the circulation of air therethrough as may be desired. Such a device as is here described is particularly useful during cold 15 weather allowing the water in the radiator to be maintained at a desired temperature and also aiding in preventing the water from freezing in extremely cold 20 weather.

An important object of the invention is to generally improve upon a shutter mechanism of this nature by providing a simple and efficient construction, one which is reliable in use and operation, inexpensive to 25 manufacture, attractive in appearance, durable, conveniently operated, and well adapted to the purpose for which it is desired.

With the above and numerous other objects in view as will appear as the description progresses, the invention resides in certain novel features of construction, and in the combination and arrangement of parts as will be hereinafter more fully described and 35 claimed.

In the drawing:

Figure 1 is an elevation of an automobile radiator showing my shutter mechanism associated therewith,

40 Figure 2 is a detail elevation showing the actuating means for the shutters,

Figure 3 is a detail section taken substantially on the line 3—3 of Figure 2,

45 Figure 4 is a detail section on an enlarged scale taken substantially on the line 4—4 of Figure 1,

Figure 5 is a detail section taken on the line 5—5 of Figure 2,

50 Figure 6 is a detail fragmentary elevation taken at substantially right angles to that shown in Figure 2,

Figure 7 is a vertical section taken substantially on the line 7—7 of Figure 1,

Figure 8 is a detail perspective view of the shutter operating block,

Figure 9 is a detail perspective of one of the position retaining devices for the shutter, and

Figure 10 is an elevation of the dash dial.

Referring to the drawing in detail it will be seen that the radiator 1 which I have illustrated may be of any preferred construction including the usual casing having therein the cooling members 2. Two angle arms or bars 3 are disposed vertically on the casing one on each side of the cooling means 2 and a plurality of shutters 4 are journaled therebetween being provided with suitable pintles 5 which project through the angle bars. These shutters 4 are so arranged that when they are in a closed position as shown in Figure 7 the edges thereof will touch each other so as to prevent circulation of air through the cooling means 2.

I have provided means whereby these 75 shutters may be actuated progressively from the top to the bottom and vice versa. Thus in extremely cold weather it would probably be desirable that only the upper shutters 4 be open as in Figure 1, whereas in hot weather it would be desirable that all of the shutters be open.

The operating means for these shutters is actuated from the dash, see Figure 4, by means of a crank 6 which is attached or formed integral with a shaft 7 preferably journaled in the dash of the automobile and through the casing of the radiator passing under the hood of the engine. The forward end of this shaft carries a beveled gear 8 which meshes with a similar bevel gear 9 carried at the upper end of the shaft 10 which is provided with a spiral groove 11 extending throughout its entire length. This shaft 10 is journaled in plates 12 carried at the ends of one of the angle bars 3. A block or nut 13 is mounted on the shaft 10 being provided with a bore 14 having diametrically opposed lugs 15 therein constructed for engaging the spiral groove 11. 95 A finger 16 extends from one corner of the block 13 for engaging dogs 18 one of which

is provided on a pintle of each shutter 4, that is the pintle which extends through the angle bar 3 upon which the plates 12 are mounted or provided. In the present illustration of the invention, a strip 19 is disposed on the casing adjacent to the shaft 10. One side of the block or nut 13 will engage this strip and thus this block will be prevented from rotation and therefore upon rotation of the shaft 10 this block will move up or down depending upon the direction of the rotation of said shaft. The dogs 18 are substantially U-shaped and are fixed to the pintles 5 at their intermediate portions. As the block 13 moves past any particular dog 18 it will engage one leg thereof causing rotation of the pintle upon which the dog is mounted thereby opening or closing the shutter associated with said dog. It is evident from a consideration of Figure 7 that the shutters have a natural tendency to remain in and return to a closed position. In order to hold the shutters in an open position or a partial open position, I have provided a plurality of clips 20 which are preferably formed of resilient metal or the like. There is one clip associated with each dog. Each clip 20 includes a body 21, an angular extension 22 and an attaching plate 23 which extends parallel with the body 21. This plate 23 is attached to the adjacent angle bar 3 by means of rivets or bolts or in any other suitable manner, thus holding the body 21 in spaced relation to the bar and in such a position that a shoe 24 formed on the body will be at all times engaged with a portion of the adjacent dog, thus tending to hold the dog and the associated shutter in whatever position it may be moved. It will also be noted that each body 21 is provided with a notch 25 at its upper end for holding a block 26 through which a pintle of the adjacent shutter is journaled.

Granting that the block 13 is in its uppermost position on its shaft 10, it will be noted that by turning the crank 6 in a counter-clockwise direction that this block will be moved downwardly because of the rotation of shaft 7, beveled gears 8 and 9, and shaft 10. As it passes by the first shutter its finger 16 will engage the first dog and rotate the same so as to cause the first or upper shutter to move to an open position in which position it will be retained by the shoe 24 frictionally engaging the dog and being so held by the resilient nature of the clip 20. This operation will be continued in relation to the remaining shutters as the block moves downwardly. The operation just described will be reversed when the crank 6 is operated in a clockwise direction.

It is thought that the construction and operation as well as the advantages of the invention will now be evident without a

more detailed description thereof. It is desired, however, to point out that numerous changes in the details of construction, combination and arrangement of parts may be resorted to without departing from the spirit of the invention or sacrificing any of its advantages.

In order to ascertain the exact location of the block 13 it is preferable to provide a dial 30 on the dash provided with suitable indicia designating the various shutters so that when the end of the crank is adjacent to one of them the location of the block 13 will be known. Of course any other suitable means may be used for this purpose.

Having thus described my invention, what I claim as new, is:

1. In a shutter mechanism of the class described, a shutter, a dog attached to the shutter, means for engaging the dog so as to open or close the shutter, and means associated with the dog for frictionally engaging the same so as to hold the shutter in an open or closed position against accidental movement.

2. In a shutter mechanism of the class described, a shutter, a dog associated with the shutter for operation thereof to a closed or open position, a shaft provided with a spiral groove, a block mounted on the shaft and provided with lugs projecting into the groove of the shaft, means for preventing rotation of the block whereby upon rotation of the shaft said block will move longitudinally of the shaft, and means on the block for engaging the dog as the block passes thereby whereby said dog is actuated to operate the shutter to an open or closed position.

3. In a shutter mechanism of the class described, a shutter, a dog associated with the shutter for operation thereof to a closed or open position, a shaft provided with a spiral groove, a block mounted on the shaft and provided with lugs projecting into the groove of the shaft, means for preventing rotation of the block whereby upon rotation of the shaft said block will move longitudinally of the shaft, means on the block for engaging the dog as the block passes thereby whereby said dog is actuated to operate the shutter to an open or closed position, and means for engaging the dog for preventing accidental movement thereof so as to hold the shutter in an open or closed position in the manner and for the purpose specified.

4. In a shutter mechanism of the class described, a plurality of shutters, dogs associated with the shutters for actuation thereof, one on each shutter, a shaft provided with a spiral groove, a block on the shaft provided with a lug disposed in said groove, means for preventing rotation of the block whereby upon rotation of the shaft said

block will move longitudinally thereof, a finger projecting from the block for engagement with the dog for actuation of the latter, and spring clips provided in association with the dogs for frictionally engaging them and preventing accidental movement thereof.

In testimony whereof I affix my signature in presence of two witnesses.

WILLIAM S. THELLMAN.
